UNITED STATES PATENT OFFICE.

OSCAR M. LEICH, OF GENOA, ILLINOIS, ASSIGNOR TO CRACRAFT, LEICH ELECTRIC COMPANY, OF GENOA, ILLINOIS.

SELECTIVE SIGNALING SYSTEM.

1,160,294.

Specification of Letters Patent. Patented Nov. 16, 1915.

Application filed April 14, 1911. Serial No 620,964.

To all whom it may concern:

Be it known that I, OSCAR M. LEICH, a citizen of the United States, residing at Genoa, in the county of De Kalb and State 5 of Illinois, have invented a certain new and useful Improvement in Selective Signaling Systems, of which the following is a full, clear, concise, and exact description, reference being had to the accompanying drawings, forming a part of this specification.

My invention relates to harmonic signal receiving devices and is more particularly applicable to those devices which are used for party line service being largely applicable to telephone or similar systems.

My invention herein contemplates the provision of a harmonic signal receiving device of such a character that it will be selectively responsive to the polarity of the impressed 20 current by which I mean that pulsating positive current may operate a given ringer, whereas pulsating negative current will not, or vice versa. The ringer is tuned to a certain frequency so that two ringers of the 25 same frequency are made selectively responsive to pulsatory or vibratory currents of opposite polarity.

My invention contemplates the provision of such a ringer which is polarized and in 30 which the polarizing magnet is not included in the magnetic circuit which causes the actuation of the armature. This I find to be necessary in order to prevent de-magnetization of the permanent magnet, thus to provide 35 permanency of the ringer. I find it also necessary to do this in order to obtain a loud signal in order that actuating currents may be used of considerable strength.

It might also be said that while a specified 40 ringer is hereinafter referred to in the following description, such specific description of the illustration set forth is merely illustrative of one form which my invention may take. I am thereby not limiting myself to 45 such specific application. I will however now describe specifically one embodiment of my invention in connection with the accompanying drawing, illustrating the same, in which:

Figure 1 is a front view of a specific form 50 of signal receiving device; Fig. 2 is a side view thereof, and Figs. 3 and 4 are details of construction.

I will now describe a specific ringer construction which I find gives me the advantages above referred to. This ringer consists of the ringer spools 1 and 2 which are united by the heel piece 3, which heel piece carries gong standards 4, 4, and gongs 5, 5. A permanent magnet 6 is united to the heel 60 piece 3, and in the ordinary form is bent forwardly at its lowermost extremity as is well understood. The spools 1 and 2 are mounted upon cores 7 and 8, carrying a spring supporting bridge formed of two 65 parts 9, 9 between which a harmonic spring 10 is placed, the three being riveted together by means of the three rivets 11, 11, 11. Nuts 12, 12 hold the bridge on the cores 7 and 8. The spring 10 is likewise riveted to two 70 parts 13 and 14 forming the armature by means of the rivets 15. The elements 13 and 14 are of course of magnetic material, the elements 9, 9 being of non-magnetic material as is well understood. The elements 13 75 and 14 carry upwardly extending arms 16 which are riveted together with a clapper rod 17 carrying the clapper 18 adapted to agitate the gongs 5, 5 when currents of the proper frequency are passed through the 80 ringer spools to bring the spring 10 into synchronism therewith to thereby vibrate the armature 13, 14. The armature 13, 14 is so arranged that it is magnetically unbalanced with respect to the cores 7 and 8, and 85 this is done by having a larger air gap between the element 14 and the core so that it will not be sufficiently close to cause the armature to vibrate should currents of a polarity which tend only to attract this portion 14 of the armature be passing through 90 the ringer spools.

The ringer spool 2 aids in a proper distribution of magnetism to direct it toward the armature for the completion of an ample magnetic density as harmonic ringers of this type require a very strong energization in view of the opposing influence of the 95

spring against which opposition the ringers operate, at least during the initial operation of the ringer.

Currents of the opposite polarity, however, which tend to attract the part 13 of the armature will, if of the proper frequency, cause the said signal receiving device to respond. This particular signal receiving device will thus be subjected to current of the proper frequency, responding only to such currents of a given predominating polarity, and will not respond to currents even if of the proper frequency but of the opposite predominating polarity.

15 By the statement "predominating polarity," I mean that while pulsating current might properly be used there might be a small loop of that current having the opposite polarity to the main loop, which would 20 however not be sufficient to interfere with the selective operation so that the ringer is responsive if the predominating polarity is of a certain sign.

It will be understood that while I claim 25 this particular construction of ringer to be novel, yet any form of ringer may be used in connection with my improved system which exhibits similar selective characteristics as the ringer just outlined.

30 In my co-pending application Serial No. 639,783, filed July 21, 1911, I show a system with which my ringer may satisfactorily operate. This system was originally disclosed herein but has been canceled from 35 this application and inserted in the said divisional application referred to. In this divisional application I set forth central station apparatus capable of producing frequencies of 30, 42, 54 and 66, both of negative and positive predominating polarity. I also set forth a substation instrument in 40 which the magneto generator thereat, which is used for calling purposes, impresses current on the line of a polarity to which the generators on the same line will respond. The various system features have been made 45 the subject matter of the co-pending application above referred to, this application being now confined to the signal receiving device proper and to the claims covering specifically and generically the particular device capable of selectively responding in answer to predetermined selections of frequency and currents of predominating polarity or other different electrical character.

50 In the claims I use the expression that the armature of the ringer is at all times in closer proximity to one of the two pole pieces than the other. By this I mean that 55 at no time during the oscillation of the armature is the part numbered 14 nearer to its respective pole piece than the part 13 gets away from its associated pole piece.

The above description will illustrate my

improved device, and may be taken as illustrative of my invention. While I have, however, thus specifically set forth one embodiment of my invention, I do not limit myself to this specific description and arrangement as herein set forth, but

Having thus described and shown my invention, what I claim as new and desire to secure by Letters Patent is:

1. A polarized harmonic ringer having two pole pieces and an armature at all times in closer proximity to one pole piece than to the other.

2. A polarized harmonic ringer having two pole pieces and an armature normally within the operative field of one pole piece only.

3. A polarized harmonic ringer having two pole pieces, an armature at all times in closer proximity to one pole piece than to the other, a permanent magnet for polarizing said armature, and a tuned spring upon which said armature is mounted.

4. A polarized harmonic ringer having two pole pieces, an armature normally within the operative field of one pole piece only, a permanent magnet for polarizing said armature, and a tuned spring upon which said armature is mounted.

5. A polarized harmonic ringer having two pole pieces, an armature at all times in closer proximity to one pole piece than to the other, a permanent magnet for polarizing said armature, a tuned spring upon which said armature is mounted, and a winding provided for the pole piece having effective relation with said armature.

6. A polarized harmonic ringer having two pole pieces, an armature normally within the operative field of one pole piece only, a permanent magnet for polarizing said armature, a tuned spring upon which said armature is mounted, and a winding provided for the pole piece having effective relation with said armature.

7. A polarized harmonic ringer having a coil, an armature in close proximity to one extremity of said coil, means for extending the magnetic circuit from the opposite extremity of said coil toward said armature, normally within the operative field of one pole piece only, a permanent magnet for polarizing said armature, and a tuned spring upon which said armature is carried.

8. A polarized harmonic ringer having two pole pieces, a winding for one pole piece, and an armature at all times in closer proximity to said last aforesaid pole piece than to the other whereby said armature responds to current of one direction only.

9. A polarized harmonic ringer having a pair of coils with associated cores and pole pieces, a permanent polarizing magnet, an armature, a tuned spring on which said

armature is mounted, said armature having arms extending toward each pole piece, one of said arms of said armature being bent away from its corresponding pole piece so that it is not in attractable relation to its corresponding pole piece.

In witness whereof, I hereunto subscribe

my name this tenth day of April, A. D., 1911.

OSCAR M. LEICH.
